CLAIM

(22) Filed: **Jul. 13, 2010**

The ornamental design for a container for stick fragrance diffusers, as shown and described.

(30) **Foreign Application Priority Data**

DESCRIPTION

Jan. 13, 2010 (DE) 00165617-4-0003

FIG. 1 is a front view of the container for stick fragrance diffusers of the present invention.

(51) **LOC (9) Cl.** **28-99**

FIG. 2 is a front perspective view of the container of the present invention.

(52) **U.S. Cl.** **D23/366**

FIG. 3 is a rear perspective view of the container of the present invention.

(58) **Field of Classification Search** D23/355-369;

FIG. 4 is another front perspective view of the container of the present invention taken at a slightly different angle than in FIG. 2.

D28/5, 6; 261/DIG. 17, DIG. 42, DIG. 65,
261/DIG. 88, DIG. 89; 392/386, 390, 391,
392/392, 393, 394, 395; 239/34, 35, 44-47,
239/50, 53, 56, 60, 145, 326

FIG. 5 is another rear perspective view of the container of the present invention taken at a slightly different angle than in FIG. 3.

See application file for complete search history.

FIG. 6 is a plan view of the container of the present invention; and,

(56) **References Cited**

FIG. 7 is a bottom view of the container of the present invention.
